UNITED STATES PATENT OFFICE

MURII MANAHAN, OF NEW YORK, N. Y., ASSIGNOR TO WECHSLER SILK CORPORATION, OF NEW YORK, N. Y., A CORPORATION OF NEW YORK

DESIGN FOR A TEXTILE FABRIC

Application filed March 6, 1933. Serial No. 47,400. Term of patent 3½ years.

To all whom it may concern:

Be it known that I, MURII MANAHAN, a citizen of the United States of America, residing at the city of New York, in the county of New York and State of New York, have invented a new, original, and ornamental Design for a Textile Fabric, of which the following is a specification, reference being had to the accompanying drawing, forming part thereof.

The figure is a plan view of a textile fabric, showing my new design.

I claim:

The ornamental design for a textile fabric, substantially as shown.

MURII MANAHAN.
